UNITED STATES PATENT OFFICE.

JAMES W. KEYSTON, JR., OF SAN FRANCISCO, CALIFORNIA, ASSIGNOR TO THE NORTH & JUDD MANUFACTURING COMPANY, OF NEW BRITAIN, CONNECTICUT, A CORPORATION.

DESIGN FOR A SPUR-BODY.

41,490.

Specification for Design. Patented June 20, 1911.

Application filed August 26, 1910. Serial No. 579,188. Term of patent 14 years.

To all whom it may concern:

Be it known that I, JAMES W. KEYSTON, Jr., a citizen of the United States, residing at San Francisco, in the county of San Francisco and State of California, have invented a new, original, and ornamental Design for Spur-Bodies, of which the following is a specification, reference being had to the accompanying drawing, forming part thereof.

The figure is a perspective view of a spur body, showing my new design.

I claim:—

The ornamental design for a spur body, as shown.

JAMES W. KEYSTON, JR.
